US00D981843S

(12) **United States Design Patent** (10) **Patent No.:** **US D981,843 S**
(45) **Date of Patent:** **** Mar. 28, 2023**

(54) **COMBINED LID AND CONTAINER**

(71) Applicant: **BRADSHAW HOME**, Rancho Cucamonga, CA (US)

(72) Inventor: **Christopher Warren Glupker**, North Hills, CA (US)

(73) Assignee: **BRADSHAW HOME**, Rancho Cucamonga, CA (US)

(**) Term: **15 Years**

(21) Appl. No.: **29/798,769**

(22) Filed: **Jul. 9, 2021**

(51) LOC (14) Cl. **09-03**

(52) U.S. Cl.

(57) **CLAIM**

The ornamental design for a combined lid and container, as shown and described.

DESCRIPTION

FIG. 1 is a front, top, right perspective view of a combined lid and container showing my new design;

FIG. 2 is an exploded view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the Figures are for the purpose of illustrating portions of the combined lid and container and form no part of the claimed design.

1 Claim, 8 Drawing Sheets
